FIG. 1 is a top front perspective view of a fixed divided cooler with a dual lid and oversized wheels showing my new ornamental design;

FIG. 2 is a rear bottom perspective view of fixed divided cooler with a dual lid and oversized wheels shown in FIG. 1;
FIG. 3 is a top front perspective view of the fixed divided cooler with a dual lid and oversized wheels shown in FIG. 1 with the dual lid open showing the divider;
FIG. 4 is a top rear perspective view of the fixed divided cooler with a dual lid and oversized wheels shown in FIG. 1 with the dual lid open showing the divider;
FIG. 5 is top view of the fixed divided cooler with a dual lid and oversized wheels shown in FIG. 1;

FIG. 6 is a top view of the fixed divided cooler with a dual lid and oversized wheels shown in FIG. 1 with the dual lid open showing the divider;

FIG. 7 is a bottom view of the fixed divided cooler with a dual lid and oversized wheels shown in FIG. 1;

FIG. 8 is a right side view of the fixed divided cooler with a dual lid and oversized wheels shown in FIG. 1;

FIG. 9 is a right side view of the fixed divided cooler with a dual lid and oversized wheels shown in FIG. 1 with the dual lid open;

FIG. 10 is a front view of the of the fixed divided cooler with a dual lid and oversized wheels shown in FIG. 1 with the dual lid open; and,
FIG. 11 is a front view of the fixed divided cooler with a dual lid and oversized wheels shown in FIG. 1.
